US00D896760S

(12) **United States Design Patent** (10) **Patent No.:** **US D896,760 S**
(45) **Date of Patent:** **** Sep. 22, 2020**

(54) **ELECTRICAL SOCKET**

(71) Applicant: **NINGBO WELL ELECTRIC APPLIANCE CO., LTD.**, Ningbo (CN)

(72) Inventor: **Guolin Yu**, Ningbo (CN)

(73) Assignee: **NINGBO WELL ELECTRIC APPLIANCE CO., LTD.**, Ningbo (CN)

(**) Term: **15 Years**

(21) Appl. No.: **29/681,581**

(22) Filed: **Feb. 26, 2019**

(51) **LOC (12) Cl.** **13-03**

(52) **U.S. Cl.** **USPC** **D13/137.3**

(58) **Field of Classification Search**

(57) **CLAIM**

The ornamental design for an electrical socket, as shown and described.

DESCRIPTION

FIG. 1 is a right, front, top perspective view of an electrical socket showing my new design;

FIG. 2 is a left, rear, bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines depict portions of the electrical socket that form no part of the claimed design.

1 Claim, 8 Drawing Sheets
